UNITED STATES PATENT OFFICE

CHARLES H. LOVETT, OF TRENTON, NEW JERSEY, ASSIGNOR TO THE COOK POTTERY COMPANY, OF TRENTON, NEW JERSEY, A CORPORATION OF NEW JERSEY

DESIGN FOR A BRACKET FOR BATHROOMS

Application filed March 12, 1930. Serial No. 34,827. Term of patent 7 years.

To all whom it may concern:

Be it known that I, CHARLES H. LOVETT, a citizen of the United States, residing in Trenton, county of Mercer, State of New Jersey, have invented a new, original, and ornamental Design for a Bracket for Bathrooms, of which the following is a specification, reference being had to the accompanying drawing, forming part hereof.

Fig. 1 is a view in elevation of the inner side of a bracket for bathrooms showing my new design;

Fig. 2 is a view in elevation of the front end thereof; and

Fig. 3 is a view in elevation of one edge thereof.

I claim:

The ornamental design for a bracket for bathrooms, substantially as shown.

In testimony whereof I have hereunto signed my name this 10th day of March, A. D., 1930.

CHARLES H. LOVETT.
